ILLUMINATED SCREW DRIVER

Elwood S. Wood, Jr., Norfolk, Va.

Application May 26, 1955, Serial No. 511,143

3 Claims. (Cl. 240—6.46)

This invention relates to a screw driver having a detachable handle with means in the handle for illuminating the end of the screw driver.

An object of the invention is to provide a compact, simple tool that can be used in an emergency, or where it is desired to concentrate a light beam at the exact spot where the screw driver is applied to a screw.

Another object is to provide a screw driver having a blade attachment with means in the handle whereby to provide a light at the tip of the screw driver blade.

Other objects will be set forth hereinafter throughout the specification.

In the drawings:

Figure 1 is a side elevation of the combined screw driver and handle;

Figure 2 is a vertical section of the structure shown in Figure 1;

Figure 3 is a view similar to Figure 1 with the handle removed;

Figure 4 is a view similar to Figure 3 of a modified form of the invention with the lower end of the blade shown in section; and

Figure 5 is a modified screw driver blade for use with a socket wrench adapter.

Referring to the drawings, the numeral 10 indicates the blade of a screw driver having a square head 12 which is adapted to seat in a square socket 14 of a handle 16.

The head 12 is held in the socket by means of a ball 18 having a spring 20 which engages a recess 22 in the socket 14, as particularly shown in Figure 2.

The handle 16 is provided with a hollow portion 24 for the reception of a flashlight 26. This flashlight may be of the structure shown herein or of the structure shown in my Patent No. 2,783,364, granted February 26, 1957. This flashlight has not been illustrated herein in order to avoid duplication in the present application and the enlargement of the showing hereof.

This flashlight is of the usual battery type and the light bulb 28 may be illuminated by turning the barrels of the flashlight. The flashlight is a self-contained unit. The relatively rotatable barrels are indicated by the numerals 30 and 30a. When one barrel is rotated relative to the other in one direction, it will come to a stop and "lock" the barrels to each other with the light on. Several companies manufacture this type of flashlight and it is preferable for many uses because of the fact that the light may be "locked" in the "on" position, and one barrel may be rotated relative to the other to "unlock" the light switch within the barrels. Other types of flashlights may, however, be used, as I do not desire to restrict the invention to a particular type of flashlight.

When the flashlight is turned on, the light beams therefrom are projected vertically upwardly as viewed in Figure 2, through the longitudinal passageway 32 of the stem of the screw driver 10 to the tip or screw engaging end of the screw driver. In this manner, and with the

2

parts assembled as shown in Figures 1-3, the beams from the flashlight bulb 28 extend through the longitudinal passageway 32 so as to properly set the tip of the screw driver in the screw slot and keep it there during normal operation of the screw driver.

It will be understood that the screw driver may be replaced by another tool, and that the screw engaging end of the screw driver may be of any suitable configuration so as to engage all types of screw heads. The engaging end or blade tip is indicated by the numeral 34. The head 12 shown in Figures 1 and 2 can be of oval or other non-circular configuration, and the socket may be of a similar configuration. In other words, any configuration between these parts may be used that will prevent relative rotation between them.

Referring to the structure shown in Figure 4, this structure includes a blade 10b having a multi-sided head 12b which fits into a corresponding socket 14b. The head 12b is provided with a ball 18b which is spring pressed outwardly by a spring 20b into a recess 22b in the adapter 36b. This adapter 36b is substantially the same shape as the squared or multi-sided head 12, i. e., it is provided with a plurality of angled sides which enable it to be received within a socket wrench, not shown. The adapter is provided with a ball 38b which is projected outwardly by a spring 40b so as to engage the socket of a socket wrench such as shown at 34 in my Patent No. 2,783,364 granted February 26, 1957, and filed on the same day as this application. The screw driver blade has a blade tip 34b. The blade, as shown in Figure 4, is provided with a longitudinal passageway 32b.

Referring to Figure 5, the blade is indicated at 60 having a blade tip 62 and an adapter or head 64 rigidly attached thereto. The adapter and blade are provided with a longitudinal passageway 66, which communicates with the socket 68. This socket may be engaged by a socket wrench, not shown, having a light source, which will project light upwardly through the aperture 66 in the same manner as light is projected upwardly through the passageway 32 in the structure shown in Figures 1-3.

It will be understood that the handle, blade and adapters shown in the several figures may be constructed of any suitable material. For instance, the handle may be plastic while the blade and adapters may be of metal, but I do not wish to be limited to the particular material used in the construction of any of these elements.

In order to set up the structure shown in Figures 1 and 2 for actual operation of the device, and assuming the parts have been entirely disassembled, the barrels 30 and 30a are rotated until the light bulb 28 is illuminated by the battery within the relatively rotatable barrels. The barrels will be "locked" in position when the light is on. The flashlight is then dropped into the hollow portion 24 of the handle. The socket 12 with the blade permanently attached thereto is slipped into the socket 14 until the ball 18 engages the recess 22. In some constructions, the recess 22 may be omitted. With the parts thus assembled, the screw driver is ready for operation, and the blade tip 34 will be fully illuminated by the light passing from the light source 28 through the longitudinal passageway 32 to the blade tip.

Of course, where the light is good, the flashlight may be removed from its recess, or it may be temporarily removed from its recess and the barrels rotated so as to turn off the light, after which it may be returned to its recess and the head 12 inserted in the socket 14.

It will be understood that the several parts illustrated in Figures 4 and 5, may be used in substitution for various of the parts shown in Figures 1-3.

Although I have shown in Figures 1-5, inclusive, a screw driver blade tip, it will be understood that other

tools can be used in place of the blade tip indicated at 34, 34b and 62, as I may wish to substitute, for instance, a socket for the blade tip which is constructed and adapted to engage a nut.

The above description and drawings disclose several embodiment sof the invention, and specific language has been employed in describing the several figures. It will, nevertheless, be understood that no limitations of the scope of the invention are thereby contemplated, and that various alterations and modifications may be made such as would occur to one skilled in the art to which the invention relates.

I claim:

1. An illuminated screw driver comprising an elongated handle, an axially arranged recess extending into said handle from one end thereof and being closed at its inner end, the outer end of said recess terminating in an enlarged blade receiving socket and providing a shoulder at the inner end of said socket, an elongated screw driver blade having one end detachably mounted in said socket, means on said one end of said blade and in said socket to prevent rotation of said blade in said socket, means on said one end of said blade to detachably secure said blade in said socket, a straight axially arranged through passageway extending from one end of said blade to the other, a flashlight fitted in said recess between its inner end and the inner end of said blade, said flashlight comprising a plurality of axially adjustable barrels rotatably connected together to vary the length

5 of said flashlight, a light bulb carried by the barrel adjacent said shoulder and located in alignment with said passageway, relative adjustment of said barrels to shorten said flashlight serving to illuminate said bulb and lock said barrels against further movement to shorten said flashlight.

10 2. An illuminated screw driver as defined in claim 1, wherein said means for preventing rotation between said blade and said socket comprises an integral multi-sided head on said one end of said blade and a corresponding multi-sided blade receiving socket.

15 3. An illuminated screw driver as defined in claim 1, wherein said means to detachably secure said blade in said socket comprises a spring actuated detent carried by said one end of said blade and normally engaging in a recess in the wall of said socket.
